H. J. Bellows
ATTORNEY.

UNITED STATES PATENT OFFICE.

ROBERT J. HARRINGTON, OF DALTON, MASSACHUSETTS.

DEVICE FOR CLEANING DRIVING-BELTS.

1,165,404.

Specification of Letters Patent.

Patented Dec. 28, 1915.

Application filed January 26, 1914. Serial No. 814,342.

To all whom it may concern:

Be it known that I, ROBERT J. HARRINGTON, a citizen of the United States of America, and resident of Dalton, in the county of Berkshire and State of Massachusetts, have invented certain new and useful Improvements in Devices for Cleaning Driving-Belts, of which the following is a full, clear, and exact description.

10 The present invention relates to a device for keeping the belt for driving machinery of various kinds constantly clean, and the invention is characterized by the provision of a revoluble belt cleaner with means in 15 which it is journaled whereby it is supported in its operative proximity to the running course of the driving belt, and means adapted to derive rotation directly from the belt to be cleaned and which in turn revolubly 20 drives the belt cleaner.

The invention is described in conjunction with the accompanying drawings and is set forth in the claims.

In the drawings:—Figure 1 is a plan view; Fig. 2 is a side elevation representing my improved belt cleaning device as in its operative relation to the running course of a belt. Fig. 3 is a sectional view taken on line 3—3, Fig. 1. Fig. 4 is a modification 30 diagram.

Similar characters of reference indicate corresponding parts in all of the views.

In the drawings, A represents the support through which the shaft B which carries the 35 revoluble belt cleaner C is rotatively supported. This support A, as shown in Fig. 3, is made with a tubular extension or boss A².

The belt cleaner carried at one end portion of the shaft B, may be any of several 40 characters having fitness to the purpose, and to be selectively employed; and as here represented, the revoluble belt cleaner is composed of a plurality of strips of flexible material such as leather or fabric confined by 45 suitable means on the shaft and adapted when the latter is rapidly rotated to have wiping engagements on the surface of the belt adjacent the running course of which the cleaner is mounted in the journal support therefor. As manifest, a rotary brush 50 may be substituted in place of the cleaner of the type mentioned.

D represents an arm which at one extremity is made with a circular aperture or bore 55 whereby it is closely fitted externally about the aforementioned tubular boss A² of the

support, it having a sidewise engagement against the shoulder a as clearly seen in Fig. 3. This form of engagement of said arm D with the cleaner shaft support A is such that the arm may be rocked or tilted relatively to the support with the axis of the latter, and of the shaft B, as its center of swinging motion. The outer extremity of the said arm D is transversely widened in hub-like formation, as indicated at b, Fig. 1, and through this hub-like extremity of the arm a shaft E is journaled,—the same being always axially parallel with the belt cleaner shaft B. The said shaft E has a roller G affixed 65 on the extremity thereof which is opposite the extremity of the shaft B, carrying the belt cleaner; and said shaft E has at its other extremity a driving wheel H of comparatively large diameter, while on the extremity of the shaft B opposite the location 70 of the belt cleaner is a wheel J of diameter very much smaller than that of the wheel H.

A driving connection I has running connection around the wheels H and J, whereby 80 the rotations of the former cause a greater number of rotations of the latter.

In the accompanying drawings, the driving means are represented as ordinary sprocket wheels and sprocket chain, but, as 85 manifest, the equivalent thereof might consist of pulleys and a belt; and in some cases it might be deemed more advantageous to employ pulleys H², J² and a belt I² as it would then be permissible to use the belt 90 open or as a crossed belt so that from a given direction of running of the roller carrying shaft E, the belt cleaner shaft could be rotated in the same direction or in the reverse direction as might in different cases be desired,—see Fig. 4.

M represents an arm, here represented as of a C-shape, the apertured hub portion of which embraces the end portion of the tubular hub extension A² of the support A and has confinement thereon by the set screw d. Said arm hub prevents displacement of the arm D in the line of the cleaner shaft axis. Said arm M is extended to adjacent an intermediate portion of the roller carrying 100 arm D, and it is provided with an offset portion f adapted to extend transversely under the arm D and to form a stop to limit the swinging motion of said arm in one direction, as such motion may be imparted 105 by the spring P which has connections with the arms D and M as best shown in Fig. 2.

- As will be readily understood, from the foregoing description and an inspection of the drawings, the device is to be mounted in such relation to the course of the running belt *x* that the roller *G* will have peripheral bearing against the face of the belt, and the cleaner *C* will have such proximity to the face of the belt as to have its wiping or dust clearing action upon the latter.
- 10 In the setting up and adjustment of the device, the support *A* will be so positioned as to maintain the roller *G* carried by the arm *D* against the belt with a yielding pressure as permitted and insured by the tiltable character of the arm, and the provision of the spring for its retractile action constantly maintains the peripheral contact notwithstanding that the belt may waver or undulate more or less as it runs.
- 15 20 And it is to be pointed out that the arm *D* is composed of two sections *g* and *h*, one of which is longitudinally adjustable relatively to the other, with means for the confinement of said sections in their adjusted relations such as the provision of the slot *i* and the headed and nut provided bolt *j*, as commonly employed for the corresponding purpose in many kinds of mechanism.
- 25 It is almost unnecessary to explain that the roller *G*, in peripheral contact against the running belt, deriving rotation therefrom drives the shaft *E*, which, through the before stated connections, drives the revoluble belt cleaner *C*.
- 30 35 The direct support *A* for the belt cleaner shaft is jointed as shown at *m* to the extremity of a rod *n* which is longitudinally as well as rotatively adjustable through or in a member *o*, and which member has an offset portion *t* which is rotatively and also longitudinally adjustable relatively to a stem or rod *u*, which latter is adjustably connected with an attachment member or foot piece *v*.
- 40 45 The manner of connection or articulation of the last described parts is such that the device constituting the essential subject matter of this invention may be supported in any situation as required by reason of the particular relation which the course of the belt may have to the primary support for the device; and in some cases the primary support may be a floor, in others the side of the machine frame; and in others the side or overhead wall or post of the building.

Changes or alterations in respect of minor

details of construction may be made without departure from this invention and without sacrificing any of the advantages thereof.

I claim:

1. A belt cleaning device including a support mounted for universal adjustment, a belt cleaner mounted in the support, a driving element having adjustable connection with the support, and a connection between said driving element and belt cleaner to operate the latter in the movement of the former.

2. A belt cleaner including a support mounted for universal adjustment, a cleaning element rotatably mounted in the support, a driving element rotatably and adjustably mounted on the support, and an operating connection intermediate the cleaning element and driving element.

3. A belt cleaner including a support mounted for universal adjustment, a cleaning element rotatably mounted in the support, a driving element rotatably and adjustably mounted on the support, and an operating connection intermediate the cleaning element and driving element, and means carried by the support to limit rotatable movement of the driving element with relation to the support.

4. A belt cleaning device including a support, a cleaning element rotatably mounted therein, an arm rotatably mounted with relation to the cleaning element, said arm comprising longitudinally adjustable sections, a driving element rotatably mounted in one of the sections, and an operative connection between the driving element and cleaning element.

5. A belt cleaning device including a support, a cleaning element rotatably mounted therein, an arm rotatably mounted with relation to the cleaning element, said arm comprising longitudinally adjustable sections, a driving element rotatably mounted in one of the sections, an operative connection between the driving element and cleaning element, a stop adjustably mounted on the support and adapted to limit rotatable movement of the arm in one direction, and a spring connecting the stop and arm.

Signed by me at Springfield, Mass., in presence of two subscribing witnesses.

ROBERT J. HARRINGTON.
